UNITED STATES PATENT OFFICE.

CHARLES J. REED, OF PHILADELPHIA, PENNSYLVANIA.

RIM-SECTION FOR EXPANSIBLE PULLEYS.

No. 806,187.

Specification of Letters Patent.

Patented Dec. 5, 1905.

Application filed February 23, 1905. Serial No. 246,963.

To all whom it may concern:

Be it known that I, CHARLES J. REED, a citizen of the United States, residing at Philadelphia, in the county of Philadelphia and State 5 of Pennsylvania, have invented certain new and useful Improvements in Rim - Sections for Expansible Pulleys, of which the following is a specification.

In United States Patents Nos. 758,474 and 10 758,561, granted to me April 26, 1904, I have shown expansible pulleys each drum of which comprises a set of radially-adjustable rim-sections the ends of which pass through radial slots in circular guide-plates and have 15 teeth entering spiral grooves in circular adjusting-disks. Both the sides and the teeth of such rim-sections ordinarily fit somewhat loosely in the guide-slots and spiral grooves to prevent undue friction and binding of the 20 sections as they are shifted to vary the diameter of the drum. This looseness permits the rim-sections which are not beneath the belt to be thrown slightly outward by centrifugal action; but the pressure of the belt 25 again forces them against the inner walls of the grooves. Each rim-section thus moves slightly forward and inward during every revolution of the pulley, and this movement occasions unnecessary noise and wear. In 30 United States Patent No. 783,311, granted to me February 21, 1905, I have shown a rim-section for pulleys of this type which is provided with resilient toothed ends to frictionally engage the sides of the guide-slots. These 35 rim-sections operate without noise, the frictional engagement preventing the sections from being thrown outward by centrifugal action. Each section, however, has four separate toothed members, which are permanently secured together, and these teeth require accurate fitting to enable them to move 40 smoothly in the adjusting-grooves.

The present invention is an improved rim-section for expansible pulleys, which consists 45 of separate notched members, each member having a belt-receiving surface and toothed ends. The sections may consist of two or more members, the outer members preferably having flanges to carry the belt. The 50 separate members may be made of thin resilient material, easily punched and flanged, and no accurate fitting is required, since the separate members can shift relatively, and thus adjust themselves in the spiral grooves. 55 The outer members are preferably bent so that their toothed ends frictionally engage

the sides of the guide-slots, while the intermediate member or members are held in place by the pressure of the outer ones.

Referring to the accompanying drawings, 60 Figure 1 is a perspective view of a rim-section consisting of two members. Fig. 2 is a plan view of the rim-section shown in Fig. 1. Fig. 3 is an end view of the rim-section shown in Fig. 1. Fig. 4 is an end view of a rim-section 65 consisting of two outer and two intermediate members, and Fig. 5 is a plan view of one end of the rim-section shown in Fig.4.

The section shown in Figs. 1, 2, 3 consists of two separate matched members 1 2, preferably punched out of sheet-steel, each of which comprises a flanged belt-receiving portion 3, a body 4, and toothed ends 5. The bodies are preferably punched with a series of holes 6 to lighten them. Each member is 75 slightly bent at its middle, so that the bodies of the two members diverge from their middle to the toothed ends 5. The ends are pressed together before inserting them in the guide-slots of the pulley, and thus bear frictionally against the sides of the slots, preventing their movement by centrifugal force. The two members being separate and unconnected can shift relatively, and thus assume 80 their proper position in the spiral adjusting-grooves.

The rim-section shown in Fig. 4 consists of two outer members 1 2, like those shown in Fig. 1, and two intermediate flat members 7, having their belt-receiving edges in line with 90 the flanges 3. A thicker rim-section is thus provided for large pulleys. The members not only assume the proper position in the spiral adjusting-grooves, but shift relatively to fit the varying curvature of the grooves as 95 they are adjusted to or from the center of the pulley.

I claim—

1. A rim-section for expansible pulleys, consisting of separate matched members, 100 each member having a belt-receiving surface and toothed ends, as set forth.
2. A rim-section for expansible pulleys, comprising two separate matched members, each member having a flanged belt-receiving 105 portion and toothed ends, as set forth.
3. A rim-section for expansible pulleys, consisting of separate outer members and an intermediate member or members, each member having toothed ends, and said outer members each having a flanged belt-receiving portion, as set forth. 110

4. A rim-section for expandible pulleys, comprising two separate matched members of resilient material, said members each having a belt-receiving surface and toothed ends and being slightly sprung apart at their ends, as set forth.

5. A rim-section for expandible pulleys, comprising two separate matched members of resilient material, said members each having a flanged belt-receiving portion and toothed ends, and being slightly sprung apart at their ends, as set forth.

6. A rim-section for expandible pulleys,

consisting of separate outer members and an intermediate member or members, each member having toothed ends, and said outer members consisting of resilient material, each having a flanged belt-receiving portion, and being slightly sprung apart at their ends, as set forth.

In testimony whereof I affix my signature in presence of two witnesses.

CHARLES J. REED.
